UNITED STATES PATENT OFFICE.

JOHN HENIGE, OF CHICAGO, ILLINOIS.

LIQUID-TREATMENT COMB.

Application filed October 14, 1925. Serial No. 62,390.

My invention relates to a device for supplying liquid to the roots of the hair and for heating said liquid before application thereof.

5 It is common practice to employ olive oil in connection with shampoos, and in order to secure desirable results, the oil should be heated before application. Various expedients have been adopted for this purpose, 10 all of which are inadequate, and the apparatus employed has been crude. In the device of my invention, I have simplified the construction, reduced the cost of manufacture and rendered the device capable of production at such reasonable cost as to make it 15 available for general use.

The device of my invention is composed of simply constructed parts that may be easily assembled and taken apart for inspection or 20 repair.

The invention will be more readily understood by reference to the accompanying drawing, in which:

Fig. 1, is a longitudinal sectional view 25 through a comb or liquid applying device constructed in accordance with my invention, and

Fig. 2, is a sectional view on the line 2—2 of Fig. 1.

30 The device of my invention comprises a handle, 10, of wood or similar material, having an axial opening for the accommodation of a tube, 11, that extends from end to end of the device. The outer or forward end of 35 the tube is closed by means of a plug, 12, and within the portion that extends beyond the handle is mounted an electric heating element, 13. This element is mounted on a core, 14, and may have an insulating shell, 15,

40 therearound. Wires, 16, are connected to the heating element and extend through the handle portion of the tube. The tube is reduced in diameter to provide a shoulder, 17, and is threaded at a point adjacent to the 45 shoulder to accommodate a nut, 18, having a flange, 19. The exterior surface of the nut is threaded at a point adjacent to the flange, 19, to receive the interiorly threaded end of the cylinder or tube, 20, which constitutes 50 the hollow head or reservoir of the comb.

The handle abuts against the nut, 18, at its forward end and at its rear end is held by means of a nut, 21, which engages the exterior of the tube, 10. The forward end of 55 the hollow head, 20, is provided with a removable closure or plug, 22, through which

the oil is supplied. A bracket, 23, may be secured by solder, to the upper outer end of the head, to provide a support for the comb in an inverted position when not in use.

60 The teeth, 24, of the comb, are provided with longitudinal passages, 25, in communication with the reservoir or space within the hollow head. These passages will, of necessity, be rather minute and no attempt is 65 made herein to illustrate the process of manufacture. In actual construction, the passages will be quite large, in diameter, except at the extremities of the teeth where the passages will be closed to a very small opening. 70 I may also find it desirable to construct the teeth of the comb as a separate element rather than as a part of the head, as shown, in which case the teeth will be soldered to the head after the drilling of the passages 75 therein. Preferably the teeth and head will be constructed of aluminum in order to assure lightness and a high coefficient of heat transmission.

80 By providing a relatively small reservoir, the heating action will be quick and certain and in view of the travel of the liquid through the long passage to the point of the teeth, any excess heat will be radiated and there is no danger of possible scalding of the 85 scalp. When the device is not in use, it will be supported on the bracket, 23, in an inverted position, and all the liquid in the passages will return to the main reservoir. When it is to be used, the heating coil, will be energized with the device in its inverted position 90 and after a moment's heating, it may be reversed in its position and the heated oil will immediately pass downward through the teeth to the point of use.

95 While the use of the device in connection with liquids that are necessarily heated is an important point, it is obvious that the device may be used for applying other liquids to the roots of the hair, such as oils, tonics etc.

100 It will be noted that the construction and assembly of the parts is very simple and the device may be taken apart and re-assembled without the use of special tools or exceptional skill. Obviously, the device is capable of much modification, and I do not wish to be limited except as indicated in the appended claims.

110 I claim:

1. In a comb of the class described, the combination with a handle, a hollow head,

and teeth having passages, of a tube extending through the handle and into said hollow head, the end of said tube within the head being closed, and a heating element within and removable through the handle end of said tube.

2. In a device of the class described, the combination with a handle, of a tube extending therethrough and projecting beyond the same, a heating element within the projecting portion of said tube, a cylinder surrounding the projecting portion of said tube and having a removable closure at its outer end, said tube being adapted to receive a liquid, and apertured teeth secured to said cylinder.

3. In a device of the class described, the combination with a handle, of a comb head and apertured comb teeth of a tube extend-

ing through the handle and into the head, a heating element within the portion of said tube within said head, a reservoir being provided in said head around said tube, and a removable closure for said reservoir at the forward end of said head.

4. In a comb, the combination of a comb head and a handle, a tube extending from end to end of said head, and handle, said head having a threaded liquid tight connection with the tube at a point adjacent to the forward end of the handle, a heating element within the said tube, the space around the heating element within the head constituting a liquid supply chamber.

In testimony whereof I have affixed my signature.

JOHN HENIGE.
